UNITED STATES PATENT OFFICE.

JOHN S. BUCKMAN, OF FLUSHING, NEW YORK.

ADJUSTABLE HAT.

Application filed June 11, 1928. Serial No. 284,451.

This invention relates to hats which are expandable to various head sizes in order to more easily and satisfactorily fit a customer and relieve the dealer of the necessity of carrying in stock an extremely large number of hats of different sizes. An important object of the invention is to provide a lady's hat of this character embodying improved features of design and construction which render it a practical, attractive and readily saleable article of millinery.

Other objects will appear hereinafter.

In the drawings:

Fig. 1 is a perspective view of the improved hat looking toward the rear thereof;

Fig. 2 a fragmentary rear perspective view showing the hat expanded;

Fig. 3 a fragmentary view upon a larger scale looking toward the inner side of the back 20 of the hat with the latter contracted;

Fig. 4 a view similar to Fig. 3 with the hat expanded;

Fig. 5 an enlarged section taken on the line 5—5 of Fig. 3;

Fig. 6 a rear view of a slightly modified form of hat; and

Fig. 7 an enlarged section taken on the line 7—7 of Fig. 6.

The hat, as shown in Fig. 1, is of the popular bell-shaped type and comprises a rounded crown 1, formed of felt, and a narrow brim 2. The brim is a strip of felt of irregular width extending entirely around the crown, overlapping it and stitched thereto as at 3 along two parallel lines. The rear portion of the brim extends downward only a slight distance below the lower edge of the crown; its front portion extends materially farther and is folded upward to form an upturned visor 4; and at one side it is formed into a bow 5. Both crown and brim are freely flexible.

Centrally of its rear side the crown is folded to form pleats 6 to render it expandable. In the present instance there are four complete pleats arranged rather close together in a group. They extend downwardly from a point near the top level of the crown clear to the lower edge of the latter, are slightly curved rearward and converge downward for a material portion of their length. The pleats are of the accordion type and form four salient ridges at the exterior of the hat. Along these ridges, just inwardly of their edges, extend lines of stitching 7 which hold the opposed folds of the pleats pinched together along substantially the length of the pleats. The back portion of the brim 2 underlaps the lower ends of the pleats 6 and are also pleated as at 8 to fold therewith. At 60 their lower ends the pleats 6 are of material depth and their depth decreases gradually toward their upper ends until they merge with the smooth body of the crown.

Adjacent the lower edge of the crown the 65 opposed folds of the pleats 6 are formed with small vertical slits 9 which are in horizontal alignment, or substantially so. The pleats form five ridges within the hat crown and the said slits are arranged adjacent these inner ridges. A narrow elastic strip 10 is trained through the slits 9. It extends for a short distance beyond the opposite sides of the group of pleats and its ends are securely stitched as at 11 to the inner side of the crown. 70 This strip is adapted to normally hold the pleats folded together and hold the hat contracted and also to guide the folding and unfolding of the pleats when the hat is put on and taken off of the head.

The crown of the hat is encircled by an outer band 12 which is so placed and proportioned as to cover and conceal the elastic strip 10 at the back of the hat and to have its lower edge conceal the lower edge of the hat crown. 85 Along its upper edge it is stitched to the crown, as at 13, and its back portion is closely stitched along its upper and lower edges to the pleats, as at 14 so that it will also fold into pleats. The band is formed of substantially nonstretchable fabric and it is adapted to limit the expansion of the hat and prevent an excessive strain upon the elastic strip 10 which might destroy the resilience of the latter or tear it loose from the hat crown.

The hat is provided with a lining 15 which covers substantially the entire inner surface of the crown and also that of the brim strip 2 and is stitched to the latter entirely along its lower edge, as indicated at 16. This lining is formed of fabric cut and arranged with its threads running on the bias with respect to the direction of expansion of the hat. This renders the lining slightly stretchable and prevents tearing thereof and breaking of its stitching 16 if the expansibility of the pleat structure should exceed the normal proportions of the lining. When properly made the lining will have sufficient fullness to expand with the pleats. If it should happen to be 110 made a trifle small, however, it will stretch sufficiently to prevent tearing.

A hat of the design and structure described is a thoroughly satisfactory and attractive article of millinery. The pleats permit the expansion of the hat to a variety of head sizes and thereby greatly reduce the number of hats which the dealer is required to carry in stock. The resilient element 10 causes a contraction of the hat to snugly fit the head and hold it firmly but comfortably in any position to suit the taste of the wearer. This element also serves to guide the folding and unfolding of the pleats and cooperates with the pleat stitching 7 to prevent rumpling of the pleats, cause them to fold along definite lines, and preserve them in the form of an attractive pattern. The outer band conceals the resilient element and the pleat apertures or slits 9 and also prolongs the life and resilience of the element by preventing excessive strain thereon. The lining is constructed to prevent rupture thereof or tearing of its stitching. Throughout, the hat is designed to avoid any annoyances or objections due to the inclusion of an expandable feature. The various parts are safeguarded from strain and deterioration. Also the expandable feature does not in the least mar the appearance of the hat. On the contrary the pleated structure, due to its design and location, adds to the attractiveness of the hat.

In Figs. 6 and 7 is shown a hat of slightly different design. Here the pleats 6^a terminate materially below the top of the crown 1^a and the latter is folded down at the back to cover the upper ends of the pleats. The pleats are not stitched along their edges as in the first form; the band 12^a is made wider to cover the pleats for most of their length, and the shape of brim has been changed. Otherwise the structure of this hat is the same as that previously described.

Both forms of the hat are thoroughly practical and desirable. However, I do not wish to be limited strictly to this disclosure of my invention but reserve the right to make such changes therein as will lie within the scope of the claims. For example, the pleats may be located at some point other than the back of the hat.

50. What I claim is:

1. An adjustable hat of generally conventional design for ladies' wear formed at one side with a few closely grouped pleats therein beginning in the crown of the hat, extending downwardly to the lower edge of the hat and adapted to fold and unfold for varying the head size of the hat while the rest of the hat has the usual outer surface, said pleats being formed with apertures in their opposed folds spaced a short distance above the lower edge of the hat; a pleat-guiding and contracting element in the form of an elastic strip trained through said apertures transversely of the pleats, secured at its ends to the inner side of the hat at opposite sides of the group of pleats

and tending to hold the latter folded and an exterior band extending around the hat and covering said elastic element.

2. An adjustable hat of generally conventional design formed at one side with a few closely grouped pleats therein beginning in the crown of the hat, extending downwardly to the lower edge of the hat and adapted to fold and unfold for varying the head size of the hat while the rest of the hat has the usual outer surface, said pleats being formed with apertures in their opposed folds spaced a short distance above the lower edge of the hat; and a pleat-guiding and contracting element in the form of an elastic strip trained through said apertures transversely of the pleats and secured at its ends to the hat at opposite sides of the group of pleats and tending to hold the latter folded.

3. An adjustable hat of generally conventional design for ladies' wear comprising a felt crown formed at its rear side with a few closely grouped pleats therein beginning in the crown of the hat extending downwardly to the lower edge of the hat and adapted to fold and unfold for varying the head size of the hat while the rest of the hat has the usual outer surface, said pleats being formed with apertures in their opposed folds spaced a short distance above the lower edge of the hat; a pleat-guiding and contracting element in the form of an elastic strip trained through said apertures transversely of the pleats permanently secured at its ends to the inner side of the hat at opposite sides of the group of pleats and tending to hold the latter folded; and an exterior band extending around the hat and covering said elastic element, stitched to said pleats to fold with them and limiting the expansion of the hat.

105

4. An adjustable hat of generally conventional design formed at one side with a few closely grouped pleats therein beginning in the crown of the hat, extending downwardly to the lower edge of the hat and adapted to fold and unfold for varying the head size of the hat; elastic means tending to hold the pleats folded; and stitching extending longitudinally along the pleats through the outer ridges thereof to hold the pleat folds pinched together along said ridges and define a pattern.

5. An adjustable hat of generally conventional design for ladies' wear formed at its rear side with a few closely grouped pleats therein beginning in the crown of the hat, converging and extending downwardly to the lower edge of the hat and adapted to fold and unfold for varying the head size of the hat, said pleats being formed with registering slits in their opposed folds spaced a short distance above the lower edge of the hat; a pleat-guiding and contracting element in the form of an elastic strip trained through said slits transversely of the pleats, secured at its

125

130

ends to the inner side of the hat at opposite sides of the group of pleats and tending to hold the latter folded; an exterior band extending entirely around the hat and covering said elastic element; and stitching extending longitudinally along the pleats through the outer ridges thereof to hold the pleat folds pinched together along said ridges and define a pattern at the back of the hat.

10 6. An adjustable hat of generally conventional design for ladies' wear formed at one side with a few closely grouped pleats therein beginning in the crown of the hat, extending downwardly to the lower edge of the hat 15 and adapted to fold and unfold for varying the head size of the hat while the rest of the hat has the usual outer surface; elastic means tending to hold the pleats folded; and a lining secured within the hat and formed of 20 material cut and arranged on the bias with reference to the direction of the hat expansion to render it stretchable.

7. An adjustable hat of generally conventional design for ladies' wear formed at one 25 side with a few closely grouped pleats therein beginning in the crown of the hat, converging and extending downwardly to the lower edge of the hat and adapted to fold and unfold for varying the head size of the hat while the rest 30 of the hat has the usual outer surface, said pleats being formed with registering slits in their opposed folds spaced a short distance above the lower edge of the hat; a pleat-guiding and contracting element in the form 35 of a narrow, elongated elastic strip trained through said slits transversely of the pleats, permanently secured at its ends to the inner side of the hat at opposite sides of the group

of pleats and tending to hold the latter folded; an exterior band extending around the 40 hat, covering said elastic element and stitched to said pleats to fold with them; and stitching extending longitudinally along the pleats through the outer ridges thereof to hold the pleat folds pinched together along 45 said ridges and define a pattern at the back of the hat.

8. An adjustable felt hat of generally conventional design for ladies' wear formed at one side with a few closely grouped pleats 50 therein beginning in the crown of the hat, extending downwardly to the lower edge of the hat and adapted to fold and unfold for varying the head size of the hat while the rest of the hat has the usual outer surface, 55 said pleats being formed with registering apertures in their opposed folds spaced a short distance above the lower edge of the hat; a pleat-guiding and contracting element in the form of a short elastic strip trained 60 through said apertures transversely of the pleats, permanently secured at its ends to the inner side of the hat at opposite sides of the group of pleats and tending to hold the latter folded; an exterior band extending entirely around the hat, covering said elastic element, 65 stitched to said pleats to fold with them and limiting the expansion of the hat to protect the elastic element; and stitching extending longitudinally along the pleats 70 through the outer ridges thereof to hold the pleat folds pinched together along said ridges and define a pattern.

In testimony whereof I hereunto affix my signature.

JOHN S. BUCKMAN.
